US00D522986S

(12) **United States Design Patent** (10) **Patent No.:** **US D522,986 S**
(45) **Date of Patent:** **** Jun. 13, 2006**

(54) **COMPLEX IMAGE PLAYER**

(75) Inventors: **Young-Sam Kwon**, Seoul (KR);
Won-Gab Byun, Seoul (KR)

(73) Assignee: **Samsung Electronics Co., Ltd.**,
Kyunnggi-do (KR)

(**) Term: **14 Years**

(21) Appl. No.: **29/228,011**

(22) Filed: **Apr. 19, 2005**

(51) **LOC (8) Cl.** **14-01**

(52) **U.S. Cl.** **D14/136**
